UNITED STATES PATENT OFFICE.

JOSEPH S. MITCHELL, OF CHICAGO, ILLINOIS, ASSIGNOR TO SULLIVAN MACHINERY COMPANY, A CORPORATION OF MASSACHUSETTS.

CORE DRILL.

Application filed April 30, 1924. Serial No. 710,180.

My invention relates to core drills.

An object of my invention is to provide an improved core lifter for such a drill. Another object of my invention is to provide 5 an improved core lifter having great elasticity and strength. A further and more specific object of my invention is to provide an improved core lifter of great flexibility and especially adapted to use with soft cores. 10 These and other objects and advantages of my invention will, however, hereinafter more fully appear.

In the accompanying drawings I have shown for purposes of illustration two 15 forms which my invention may assume in practice.

In these drawings,—

Fig. 1 is a central longitudinal sectional view through a core barrel and drill bit in 20 which my improved core lifter mechanism is incorporated, the section through the lifter being taken on line 1—1 of Fig. 2.

Fig. 2 is a plan view, partially broken away to facilitate illustration, of my improved core lifter.

Fig. 3 is a side elevation of Fig. 2.

Fig. 4 is an enlarged detail sectional view showing the spring holding means.

Fig. 5 is a detail sectional view of a modified form of construction.

In the illustrative embodiment of my invention shown in Figs. 1 to 3, I have shown a hollow core barrel 1, of usual form, having a core lifter shell or casing 2 threaded 5 thereto at its upper end, as at 3, while at its lower end it is threadedly connected, as at 4, to a core drill bit 5, herein of the usual rotary diamond type, adapted to cut a core which passes up through a core lifter, generally designated 6, and of improved form 40 hereinafter more fully described.

In my improved construction the core lifter, generally designated 6, comprises a plurality of radially disposed wedge members 7 having vertical concave surfaces 8 which form an annular passage 9 through which the core is directed by means of inclined surfaces 10 formed on the lower inner edge of the wedge members. The outer periphery of each of these wedges is also provided with a reduced portion 11 in which a flat sheet metal spring 12 shaped like a truncated cone and having great elasticity is disposed, the spring herein being rigidly held in place by rivets 13 and 14. It will

be noted that the wedges 7 are provided with enlarged counterbores 15 (see Fig. 4) into which the surrounding metal of the spring is peened as at 16 and riveted, the rivets having heads 17 peened or headed over in 60 counter bores formed in the spring and in the outer surfaces of the wedge members, thereby forming a very rigid and compact construction in which the outer peripheries of the spring and the wedges engage the 65 walls of a conical bore 18 formed in the casting 2 in which the core lifter is disposed. It will also be observed that one of the wedges and the spring member 12 are split as at 19 to permit free expansion and contraction of the core lifter. In the form of my invention shown in Fig. 5, I have shown the radially expansible spring member 12 securely held to wedges 20 by means of spot welding instead of rivets, the spot welds 75 being indicated herein at 21.

As a result of my improvement, it will be noted that a core lifter having great elasticity and strength is provided, and one which permits the ready passage of the core 80 up through the same, while yet permitting the core lifter to rigidly grip even a worn core.

While I have in this application specifically described two forms which my invention may assume in practice, it will be understood that these forms of the same are shown for purposes of illustration and that the invention may be modified and embodied 85 in other forms without departing from its 90 spirit or the scope of the appended claims.

What I claim as new and desire to secure by Letters Patent is:

1. A core lifter comprising separate spaced wedge shaped core engaging members having inclined external surfaces, a conical shaped split spring encircling said members, and means for rigidly securing each of said members to said spring.

2. A core lifter comprising separate spaced wedge shaped core engaging members having inclined external surfaces, a conical shaped split spring encircling said members, and means for rigidly securing each of said members to the inner surface of said 100 spring.

3. A core lifter comprising separate spaced wedge shaped core engaging members having inclined external surfaces, a radially 105 expandible tapered split spring encircling 110

said members, and means for rigidly securing each of said members to said spring.

4. A core lifter comprising separate spaced wedge shaped core engaging members each having an external inclined reduced portion whereby a recess is formed in each member, a radially expandible split spring of truncated cone shape disposed in said recesses, and means for rigidly securing each of said members to said spring.

5. A core lifter comprising separate spaced wedge shaped core engaging members each having a projecting shoulder, a radially expandible conical shaped split spring, the shoulders on said members underlying the bottom edge of said spring, and means for rigidly securing each of said members to said spring.

6. A core lifter comprising separate spaced wedge shaped core engaging members each having a projecting shoulder and inwardly inclined core guiding surfaces, a radially expandible conical shaped split spring, the shoulders on said wedge members underlying the bottom edge of said spring, and means for rigidly securing each of said wedge members to said spring.

7. A core lifter comprising separate spaced wedge shaped core engaging members each having apertures formed therein, said apertures having enlarged outer ends, a split resilient member having portions depressed into the enlarged portions of said apertures, and means including elements disposed in said apertures for rigidly securing said wedge members to said resilient member.

8. A core lifter comprising separate spaced wedge shaped core engaging mem-

bers each having an aperture formed therein, said apertures having enlarged ends, a split 40 resilient conical shaped member encircling said wedge members and having portions depressed in the enlarged ends of said apertures, and means including elements disposed in said apertures for rigidly securing 45 each wedge member to said resilient member.

9. A core lifter comprising separate spaced wedge shaped core engaging members each having an inclined outer surface 50 and an inwardly inclined core guiding surface, a split spring formed in the shape of a truncated cone and encircling said wedge members, and means for rigidly securing said spring to the outer surface of 55 each of said wedge shaped members.

10. A core lifter comprising separate spaced wedge shaped core engaging members, each having a reduced outer surface 60 and an outwardly projecting shoulder, a split resilient member of truncated cone shape disposed against said reduced outer surfaces and engaging said shoulders, and means for rigidly securing each wedge shaped member to said resilient member. 65

11. A core lifter comprising a plurality of wedge members, a resilient member, and means for securing said resilient member to said wedges including a counterbore formed in said wedges into which the surrounding metal of the resilient member is peened and means for riveting said resilient member thereto. 70

In testimony whereof I affix my signature.

JOSEPH S. MITCHELL.
